RAND S. BAILEY, OF MONTCLAIR, NEW JERSEY, ASSIGNOR TO AMERICAN TELEPHONE AND TELEGRAPH COMPANY, A CORPORATION OF NEW YORK.

TELEPHONE SWITCHBOARD.

Application filed November 20, 1924. Serial No. 751,181.

This invention relates to telephone switchboards and more particularly to an arrangement of subscribers' multiple and answering jacks in a manual switchboard.

5 Heretofore, each line served in a so-called multiple switchboard terminated in an answering jack before a particular operator and a plurality of multiple jacks regularly placed in the switchboard so that every operator had access thereto. In accordance with this arrangement the line numbers of the lines appearing at the various answering jacks did not in any way correspond with the numerical designation of such jacks, in 10 other words, there was no orderly way in which the variously numbered subscribers' lines appeared in the answering jacks. Through such an arrangement the answering jack appearances of the subscribers' lines 15 could be shifted in order to equalize the traffic load before the various operators, and switchboards of this nature have found wide commercial application and have proved highly successful.

20 Thereafter, in the course of time and due to the ever increasing development and improvement of such switchboards, the multiple answering jack switchboard was developed wherein each line appeared in several 25 answering jacks before several operators and the operator first available for the service answered. Such an arrangement has been 30 such a success that it has led to a still further development which is embodied in the 35 present invention.

It was believed that if the subscribers' answering jacks were multiplied throughout the switchboard and the ordinary multiple jacks were entirely eliminated that the lines could 40 be arranged in numerical order and that the traffic could be equalized because every line would appear in an answering jack before every operator. Since the lines would be arranged in numerical order the answering 45 jacks could be used for outgoing as well as for incoming service and hence the efficiency of the apparatus could be raised. Again the well-known intermediate distributing frame used for shifting the answering jack appearances could be entirely eliminated. However, it was found that by using the smallest 50 size commercial apparatus available the capacity of such an exchange would be limited to a figure under that employed in the com-

mercial exchanges of today. Moreover, it 55 was found that an operator was always inclined to answer the incoming calls which were within easy reach without regard to the order in which calls originated and that hence the very trouble which such a switchboard was expected to remedy would become aggravated in the case of those lines not within easy reaching distance of the operator. It was therefore necessary to still further limit the capacity of the exchange to a 60 number of lines considerably smaller than the number which it would be possible for one operator to reach.

The object of the present invention is to 65 overcome the difficulties above mentioned 70 and by so doing to produce a switchboard wherein the speed of operation will be increased, the apparatus will be more efficiently utilized and a saving will be accomplished through the elimination of certain 75 other apparatus heretofore considered essential.

A feature of this invention is the arrangement in an orderly manner of the total number of lines in the exchange before each operator partly in multiple answering jacks 80 and partly in multiple jacks.

In accordance with this feature just so many lines appear in answering jacks before an operator as she may easily reach and the 85 remainder appear in multiple jacks before her within reaching distance. Thus while the entire multiple is accessible to one operator the service on none of the lines is slowed down on account of any psychological difficulty, that is, the jacks which she may employ at will for answering calls are placed near at hand while the jacks which she must employ in completing calls are placed further away.

90 Another feature of the invention is the orderly arrangement of the lines as they appear both in the answering jacks and the multiple jacks. That is, the lines in the answering jack group as well as the lines in the multiple jack group are in numerical sequence.

95 A further feature of the invention is the manner in which one group of lines is arranged to appear before one group of operators in answering jacks and before other operators in multiple jacks.

100 Another feature of the invention is the

entire elimination of the intermediate distributing frame even though a large number of lines is involved.

To attain these objects in accordance with one feature of the invention, all the switchboards of the exchange may, for example, be divided into two groups with all the lines incoming to the exchange accessible to each group; one portion of the lines representing by answering jacks and lamps and the other portion represented by ordinary multiple jacks in one group of switchboards while in the other group the lines represented by answering jacks and lamps in the first group may be represented by multiple jacks and the lines represented by multiple jacks in the first group represented by answering jacks and lamps.

To carry out this invention an arrangement such as shown in the attached drawing may be employed. In Figure 1 is shown, the general arrangement of a unit of operators' switchboards in which all the lines are represented; one portion of the lines by answering jacks and lamps and the other portion by multiple jacks. In Fig. 2 is shown an enlarged part of a switchboard showing the relation of the individual strips of jacks and lamps to each other. In Fig. 3 is shown the grouping of the switchboards in an exchange and a method of changing the lines from one group of switchboards to another.

Referring now to the drawings, and particularly to Fig. 1 which illustrates the arrangement in an exchange having 8,000 lines, eight panels of standard switchboard multiple 7 to 14 respectively, are shown in which one half or 4,000 of the lines are represented by answering jacks and lamps in a lower portion 5 and in which the other half or 4,000 lines are represented by ordinary multiple jacks in an upper portion 6. Each of these panels 7 to 14 is arranged as follows: In portion 5 each panel is provided with five groups of 100 lines each, subdivided in five horizontal rows with a strip of twenty answering jacks and a strip of twenty lamps in each row. The jacks and lamps in the lowermost part of the first group of 100 lines of panel 7 represent lines 0 to 19, while the next row immediately above it represents lines 20 to 39 and the remaining rows in this group are numbered consecutively in the same manner, with the fifth row numbered from 80 to 99. The first or lowermost group of 100 lines of panel 8 is arranged in the same manner with the lines numbered from 100 to 199 and the lines in the lowermost group of 100 lines in the succeeding panels 9 to 14 are numbered consecutively in the same manner, that is, so that the fifth row in the lowermost group of 100 lines in panel 14 will be numbered from 780 to 799. The second groups of 100 lines

in these panels are numbered consecutively in the same manner from 800 to 1,599 and the succeeding groups are respectively numbered 1,600 to 2,399 for the third group, 2,400 to 3,199 for the fourth group, and 3,200 to 3,999 for the fifth or last group.

In the upper portion 6 of this switchboard, the remaining 4,000 lines are represented by multiple jacks only and arranged in a manner identical with that of the first 4,000 lines. That is, each panel contains five groups of 100 jacks each, subdivided in five strips with twenty jacks in each strip and the lines in these panels are numbered from 4,000 to 7,999.

Fig. 2 shows a portion of a panel in which the answering jacks 20 and corresponding lamps 21 are arranged as they will be in portion 5 and the multiple jacks 22 as arranged for portion 6.

As is usual in manual switchboards each operator's position is provided with cords with corresponding answering and calling plugs placed on the shelves as indicated at 25.

For ordinary traffic in switchboard, arranged according to this invention, there would be provided one operator for each three panels, but it has been found that during slack periods of traffic, one operator alone may be able to attend to all of 8,000 lines. In such a case this single operator would be placed in before one line of switchboards, such as 26, immediately adjacent to the second line of switchboards, such as 27. The space occupied by these 8,000 lines is of such dimensions in the horizontal and in the vertical direction that one operator may conveniently reach any one of the jacks and readily see any one of the 4,000 answering lamps when lighted in either one of the two lines of switchboards. In answering a call she would insert the answering plug most conveniently at hand or near an answering jack, the corresponding lamp of which is lighted, and she would find the desired jack among the 8,000 by the usual procedure of reading the numbers on the subscriber's line jacks, and then insert the corresponding calling plug in the desired jack regardless of what panel or portion of the switchboard it may be located. In this arrangement it is, of course, immaterial whether the jack of the line desired is an answering or a multiple jack as connection may be made to either type equally well in answering a call as is well known in the art.

The reason the answering jacks and lamps are placed in the lower portion 5 is that the space occupied thereby is of such dimensions that when a lamp is lighted it is entirely within the line of vision of a single operator located at the switchboard and it is therefore unnecessary for the operator to search the board for incoming calls by

any excessive movements of her eyes or any other part of her body. The temptation of giving preference to answering jacks immediately in front of the operator is, therefore, to a large extent, eliminated by this invention. It is altogether possible to arrange the answering jacks and lamps of 4,000 subscribers and the multiple jacks of another 4,000 subscribers within reach of a single operator and it has been found that the space occupied by 4,000 answering jacks and lamps is in the neighborhood of five feet and eight inches in the horizontal direction and about one foot and nine inches in a vertical direction while the space occupied by the multiple jacks is the same in the horizontal direction and approximately ten inches in the vertical direction thus giving a total dimension of the switchboard in the horizontal direction of five feet eight inches and in the vertical direction of two feet and seven inches. The above number of subscriber's lines and corresponding dimensions of the switchboard are as stated, more or less approximate and it is entirely practical to arrange the switchboards with larger numbers of subscribers' lines within reasonable limits and in a similar manner.

Fig. 3 illustrates how the jacks and lamps in this group of eight panels of multiple in which all the lines incoming to the exchange are represented, may be multiplied to other groups of eight panels and how one-half of the switchboards of the exchange as shown at 26 may have 4,000 of the lines represented by answering jacks and lamps in the lower portion 5, and the remaining 4,000 represented by multiple jacks in the upper portion 6 and the other half of the switchboard as shown at 27 may have the jacks and lamps arranged in the same manner but with the positions of the two groups of lines inverted. The cables for these lines may be run in any convenient manner behind the switchboard and at the junction of the two groups of switchboards 26 and 27 a space 28 may be provided for bringing the cables 29 for the answering jacks of 4,000 lines from the lower section 5 of group 26 to the upper section 6 of group 27 where these lines are represented by multiple jacks only and for bringing the cables 30 from the answering jacks in group 27 to the upper portion 6 of the group 26. The cables for both groups of lines may enter from the terminal room at the left of group 26, or a portion of the cables for group 27 may enter between 26 and 27, as desired.

It is, of course, understood that the invention is not limited to the particular arrangement shown and may be carried out in any other manner with the principle of the invention in mind. As for example, if the total number of subscribers' lines in the exchange is 9,000, these lines may appear

before three groups of operators instead of the two groups, shown at 26 and 27. In this case, each group might be arranged so that one-third of the lines are accessible to a single operator through answering jacks and lamps and the other two groups of lines accessible to this operator through multiple jacks. Each of these three groups of switchboards would therefore have a different group of lines appearing with answering jacks and lamps. A convenient arrangement in this instance would be to have but six panels arranged for the 9,000 lines with 500 answering jacks and lamps and 1,000 multiple jacks in each panel. The dimensions of these six panels would then be approximately three feet five inches in a vertical direction, and four feet three inches in a horizontal direction.

What is claimed is:

1. Switchboards comprising operators' positions and subscribers' lines terminating thereat, having answering jacks and lamps only representing one portion of said lines located at said operators' positions within relatively easy reach of but a single operator, and multiple jacks only representing the remaining subscribers' lines placed in said positions relatively less accessible to said single operator.

2. Switchboards comprising operators' positions and a large group of subscribers' lines terminating thereat, having answering jacks and lamps only representing one-half of the total number of subscribers' lines located within relatively easy reach of but a single operator, and multiple jacks only representing the remaining lines placed at said positions in a zone relatively less accessible to said single operator.

3. Switchboards comprising operators' positions divided into two groups, subscribers' lines terminating in jacks and lamps only at the positions of one group, and terminating in multiple jacks only at the positions of the other group, subscribers' lines terminating in jacks and lamps only at the second mentioned group of positions, and in multiple jacks only at the first mentioned group of positions, the jacks and lamps in each group of positions being placed within relatively easy reach of a single operator at said group of positions, while the multiple jacks in each group are placed outside of said easily accessible zone, but still within reach of a single operator at said group of positions.

4. Switchboards comprising operators' positions and subscribers' lines terminating thereat, with one portion of the subscribers' lines appearing with answering jacks and lamps only and the remaining portion with multiple jacks only at one group of positions, and with the first mentioned portion of the subscribers' lines appearing with mul-

- 4 tiple jacks only and the second mentioned portion of the subscribers' lines appearing with answering jacks and lamps only at the second group of operators' positions, all of said subscribers' lines at each group of operators' positions being accessible to each operator at said positions.
5. Switchboards comprising operators' positions and subscribers' lines terminating thereat, with one-half of the total number of subscribers' lines appearing with answering jacks and lamps and the other half of the subscribers' lines appearing with multiple jacks at one-half of the total number of operators' positions, and with the first mentioned half of the subscribers' lines appearing with multiple jacks and the second mentioned half of the subscribers' lines appearing with answering jacks and lamps at the other half of the total number of operators' positions, all of the subscribers' lines terminating at each half of the total number of operators' positions being accessible to each operator.
- 10 6. Switchboards comprising operators' positions and 8,000 subscribers' lines terminating thereat, with 4,000 subscribers' lines appearing with answering jacks and lamps arranged in alternate horizontal strips of 20 jacks and 20 lamps, with 500 jacks and 500 lamps in each panel making a total of 8 panels, and with these answering jacks and lamps consecutively numbered throughout the 8 panels, beginning with the numeral 0 for the first left-hand jack and lamp in the lowermost left-hand strips of the first left-hand panel, and ending with the numeral 3,999 for the last right-hand jack and lamp of the uppermost right-hand strips in the last right-hand panel, and with the same 4,000 subscribers' lines appearing in the other groups of 8 panels each with answering jacks and lamps arranged and numbered in the same manner, all of said groups of 8 panels each constituting one-half of the total number of positions, the remaining 4,000 lines appearing with multiple jacks arranged in
- 15 the same manner in said groups of panels above the answering jacks and lamps, the manner of numbering these multiple jacks being also the same, except that the numbers begin with the numeral 4,000 and end with the numeral 7,999; the 8,000 lines also appearing with answering jacks and lamps and multiple jacks arranged in the same manner in the remaining panels, but with the lines arranged in the reverse order and with the numbering also reversed so that the lines retain their originally assigned numbers.
- 20 7. Switchboards comprising operators' positions and 8,000 subscribers' lines terminating thereat, with 4,000 lines appearing in one group of positions with answering jacks and lamps occupying a space approximately five feet eight inches in a horizontal direction, and one foot nine inches in a vertical direction, and with the remaining 4,000 lines appearing at the same positions in the upper portions thereof, with multiple jacks occupying a space having the same dimension in the horizontal direction as the space occupied by the jacks and lamps representing the first mentioned 4,000 lines and measuring approximately 10 inches in a vertical direction.
- 25 8. Switchboards comprising operators' positions and subscribers' lines terminating thereat, each line terminating either in a jack and lamp or a multiple jack in a position in each of a plurality of groups of positions.
- 30 9. Switchboards comprising operators' positions and subscribers' lines terminating thereat, said positions being arranged in a number of groups with a number of positions in each group, the positions in each group being again divided in an equal number of sub-groups, and all of said lines terminating in each sub-group with either an answering jack and lamp or else with a multiple jack only.
- 35 In testimony whereof, I have signed my name to this specification this 18th day of November 1924.

RAND S. BAILEY.
